UNITED STATES PATENT OFFICE.

JULIUS WONDOLOWSKI, OF NEW YORK, N. Y.

DESIGN FOR A RADIO LOUD SPEAKER.

Application filed July 27, 1927. Serial No. 22,892. Term of patent 7 years.

To all whom it may concern:

Be it known that I, JULIUS WONDOLOWSKI, a citizen of Poland, residing at New York, in the county of New York, and State of New York, have invented a new, original, and ornamental Design for a Radio Loud Speaker, of which the following is a specification, reference being had to the accompanying drawing, forming a part thereof.

Fig. 1 is a front elevational view of a radio loud speaker showing my new design.

Fig. 2 is a side elevational view of the same.

I claim:

The ornamental design for a radio loud speaker, as shown.

In testimony whereof I have affixed my signature.

JULIUS WONDOLOWSKI.
